CLAIM

The ornamental design for an equipment rack bracket for an electronic rack system or other similar systems, as shown and described.

DESCRIPTION

FIG. 1 is a perspective view of an equipment rack bracket for an electronic rack system, showing our new design;

FIG. 2 is a front view thereof;

FIG. 3 is a rear view thereof;

FIG. 4 is a top plan view thereof;

FIG. 5 is a bottom plan view thereof;

FIG. 6 is a left-side view thereof; and,

FIG. 7 is a right-side view thereof.
